UNITED STATES PATENT OFFICE.

SOLOMON A. WOODS, OF BROOKLINE, AND HOSEA R. TILLISON AND CHARLES W. H. BLOOD, OF BOSTON, MASSACHUSETTS, ASSIGNORS TO THE S. A. WOODS MACHINE COMPANY, OF BOSTON, MASSACHUSETTS.

PLANING-MACHINE.

SPECIFICATION forming part of Letters Patent No. 624,886, dated May 9, 1899.

Application filed June 12, 1893. Serial No. 477,375. (No model.)

To all whom it may concern:

Be it known that we, SOLOMON A. WOODS, of Brookline, county of Norfolk, and HOSEA R. TILLISON and CHARLES W. H. BLOOD, of Boston, county of Suffolk, State of Massachusetts, have invented an Improvement in Planing-Machines, of which the following description, in connection with the accompanying drawings, is a specification, like letters on the drawings representing like parts.

In wood-planing machines having a preparatory under cutter located in advance of the regular upper and under cutters, particularly when such machines are employed for molding purposes, it is necessary to provide a longitudinal guide-bar to prevent twisting or skewing of the stock and to guide or direct the stock to the cutting or molding knives. This guide-bar must extend either continuously or in sections substantially the entire length of the machine, or from the feeding-in end up to the side heads near or at the rear end, and the said guide-bar should preferably be made adjustable toward and from the longitudinal center of the bed in order that narrow stock might be run through the middle of the machine, where it would be centrally and evenly acted upon by the feed-rollers, rather than along one edge of the bed, as would be necessary were a fixed guide at one edge of the bed employed, and wherein the feed-rollers act unevenly upon the stock and cause the latter to work away from the guide-bar and out of proper alinement with relation to the molding-knives. The guide-bar should also be made adjustable in order that the wear upon the bed be more uniformly distributed over the entire surface of the bed instead of being confined to one edge.

Continuous adjustable guide-bars have been heretofore used in molding-machines not having a preparatory under cutter, for in such machines said guide-bar may be run continuously from the feeding-in end of the machine to the side heads at the rear end without reaching and interfering with the regular under cutter beyond or back of the side heads; but in machines having a preparatory under cutter it has heretofore been considered undesirable to employ a single continuous guide-

bar, because such guide-bar when made continuous must pass over the said preparatory under cutter. This is objectionable for the reason that it is frequently necessary to lift out or remove one or both the chip-breakers or cutter-bars at opposite sides of the preparatory under cutter to gain access to said under cutter for sharpening purposes and adjustment, and these chip-breakers or bars cannot be lifted out, if a continuous guide-bar extends over them, without first removing the entire guide-bar. Because of this difficulty it has, so far as we are aware, been the uniform practice of builders to break this long edge guide-bar at the first or preparatory under cutter—that is, form said guide-bar in two independent pieces or members terminating at opposite sides of the under cutter, but separated thereat sufficiently to permit the chip-breakers or cutter-bars to be lifted out of their sockets to permit access to the cutter. This construction, however, is objectionable, for the reason that the guide-bars are usually made adjustable and the ends of the guide-bars adjacent and terminating at the under cutter must be firmly secured against displacement, and as the feed-rollers, gearing, presser-bars, and other mechanism are necessarily massed together at this point it is exceedingly difficult to get at the fastening or adjusting devices for the frequent adjustment of the guide-bars necessary for various classes of work. Again, great care and nicety of adjustment are required to so adjust these independent guide-bars that they stand in perfect alinement.

One of the principal objects of this present invention is to devise a construction wherein a single continuous guide-bar may be employed extending in an unbroken piece from the feeding-in end of the machine to the side heads at the rear end and passing over and clearing the preparatory under cutter and its chip-breakers or cutter-bars and make the said guide-bar preferably freely adjustable toward and from the longitudinal center of the bed, yet at the same time provide some means of access to the preparatory under cutter for sharpening and adjusting without necessitating the setting back or removal of the

continuous guide-bar. This we have accomplished in a single machine by combining with a continuous guide-bar a preparatory under cutter removable endwise from the machine and from beneath the said continuous guide-bar, whatever the position of the latter, without disturbing the position or adjustment of the said guide-bar, the chip-breakers or cutter-bars also preferably remaining in position beneath the guide-bar and not removable with the cutter.

The invention also comprehends various features of construction, to be hereinafter described, and pointed out in the claims.

15 In the drawings, Figure 1 represents in side elevation one form of a planing and molding machine embodying this invention; Fig. 2, a top or plan view of the same; Fig. 3, a perspective view showing the housing in which the endwise-removable under cutter is mounted; Fig. 4, a top or plan view of the same, showing the cutter with its bearings in position; Fig. 5, a vertical cross-section taken on the dotted line $x-x$, Fig. 2, a part of the 20 presser-shoes being removed; Fig. 6, a detail looking from the feeding-in end of the machine, showing the swinging cross-bar to which the presser-shoes are attached; Fig. 7, a top or plan view of Fig. 6; Fig. 8, a cross-section 25 on dotted line $x'-x'$, Fig. 6; Fig. 9, a sectional detail showing the side-head-supporting bar, with the collar to which the rear end of the continuous guide is pivoted; Fig. 10, a detail showing the manner of attaching the front 30 end of said guide-bar to the bed; Fig. 11, an enlarged detail showing one of the side-head spindles with its bearing and chip-breakers; Fig. 12, an enlarged detail looking at the rear 35 end of the machine, showing the manner of hanging the swinging table; Fig. 13, a perspective detail showing the under-cutter bearings and connecting-yoke, and Fig. 14 is an enlarged detail in plan of one of the chip-breakers.

40 Referring to the drawings, A represents the frame, B the driving-shaft, provided with suitable pulleys B', C the bed, D the feed-rollers, and E E' the side-head spindles, all of which are and may be of usual construction 45 and may be varied in many ways without affecting this invention.

45 F represents the preparatory under cutter, journaled at its ends in suitable bearings f, shown as and preferably connected by a side 50 yoke f', holding the two bearings in proper relative positions. These bearings f are fitted to slide in suitable ways f², formed in the sides of a housing f³, provided at its ends with necks f⁴, which rest in suitable seats 55 formed in the frame A of the machine, said housing being preferably supported upon suitable adjusting devices, as the vertical adjusting-screws f⁵, (shown principally in dotted lines, Fig. 1,) said screws having their bearings in lugs f⁶, formed on the inner sides of the frame and preferably extending down below the said frame, as shown, to permit con-

venient access for adjusting the under cutters. The housing f³ is provided with suitable sockets or recesses f⁷ to receive and support the usual chip-breakers or cutter-bars f⁸, which face and extend over the cutter F in usual manner, as shown in Fig. 1. The chip-breakers or cutter-bars are preferably supported in their sockets upon adjusting-screws f¹⁰, by means of which they are adjusted vertically with relation to the cutter. The housing f³ is also provided at its under side with an outlet shaving-spout f⁹, which preferably extends to and through one side of the frame 80 to conduct away the shavings and prevent the latter being scattered throughout the inside of the machine.

G represents the regular upper cutter, and H the regular under cutter, the latter arranged at the rear end of the machine and mounted in suitable adjustable bearings, to be described.

90 The side-head spindles E E' are journaled in usual manner in suitable boxes or bearings e e', mounted upon the preferably square horizontal supporting-bars e² e³, carried in the frame, said side-head bearings, with their spindles and cutters, (the latter not being shown,) being adjustable laterally toward 95 and from the longitudinal center of the bed of the machine by suitable mechanism not constituting a part of this invention.

95 In accordance with one part of this invention we have provided a single continuous 100 edge guide-bar m, provided at its front feeding-in end with suitable adjusting devices, shown as T-bolts m', which slide across the bed C in usual T-grooves m² and furnish means for clamping the guide-bar in adjusted 105 position. The bolts m' pass through elongated holes or slots m³ in the guide-bar (see Fig. 10) for a purpose to be hereinafter referred to. The guide-bar at its rear end, adjacent the side-head spindles, is pivoted 110 at m³ to a sliding carrier, herein shown as a collar m⁴, and preferably made to serve as a clamp, mounted upon one of the side-head-supporting bars e² or e³, herein shown as the bar e³. The guide-bar at its front end is provided with a removable pin m⁵, adapted to be inserted in one of a series of holes m⁶ in a plate m⁷, herein shown as set into and flush 115 with the surface of the bed C and made adjustable longitudinally—i. e., crosswise the bed 120 therein—by means of slots in its ends and screws m¹¹, passing through said slots. The collar or clamp m⁴ at the rear end of the guide-rod is pivoted is also provided with a 125 removable pin m⁸, adapted to be inserted in any one of a series of holes m⁹ in one of the side-head-supporting bars, as the bar e³, holes 130 of the two series m⁶ and m⁹ being similarly spaced. These holes, the walls of which constitute one form of stop-surface, together with the coöperating positioning devices, shown as pins, furnish ready means for adjusting the guide-bar m in perfect alinement into any

position nearer to or farther from the longitudinal center of the bed, for the bolts m' may be slackened and the front end of the guide-bar moved toward or from the center of the bed to the desired point and pinned in place by dropping the pin m^5 in the desired hole, as shown by dotted lines, and then the operator may move or slide the clamp m^4 and the rear end of the guide-bar into like position, determined by the number of holes through which it is moved and pinned in place in like manner, the said clamp m^4 being provided with suitable clamping devices, as the bolts m^{10} , by which it may be clamped frictionally in any position into which it has been adjusted. The slots m^x in the guide-bar, through which the clamping devices m' are passed, permit either end of the guide-bar to be swung into position in advance of the other end. As the holes of the two series are spaced regularly from each other, the guide-bar when moved a distance represented by a certain number of holes at either end must of necessity be in perfect desired alignment, the guide-bar being thus movable step by step for adjustment by regular predetermined distances.

In many classes of work it is desirable to place the guide-bar in a slightly-diagonal position on the bed and with relation to the direction of feed, so as to cause the stock as it is fed through the machine to hug the guide tightly throughout its entire length. For this reason we have provided the plate m^7 , which constitutes a support, said plate being adjustable crosswise of the bed. The operator having determined at what angle he wishes the guide-bar to stand or how much nearer the longitudinal center of the machine he wishes to place the rear end of the guide-bar than the front end, he adjusts the plate m^7 into such position as will give the desired angular position of the guide-bar, and thereafter the guide-bar may be moved bodily toward or from the longitudinal center of the bed a definite number of holes and pinned in position, yet always preserve the same angularity to cause the stock to hug it. By referring to the drawings it will be seen that this guide-bar m extends continuously from the feeding end of the machine to the side-head spindles in an unbroken piece over the preparatory under cutter F , so that the entire guide-bar may be easily moved from and by its ends where easy of access without requiring any adjusting devices whatever adjacent the said preparatory cutter where they would be difficult of access. Access to the cutter, however, may be easily had by drawing the bearings f , which are connected by the yoke f' for this purpose, out from the housing f^3 at one side of the machine, as shown in dotted lines, Figs. 2 and 4, without in any way disturbing the guide-bar m , which may remain in its adjusted position at or near the center of the bed, the chip-breakers or cutter-bars f^8 also remaining in their positions under the guide into which they have been adjusted by the adjusting

screws f^{10} , upon which they rest. We are thus enabled to use the very desirable continuous guide-bar and make the same adjustable into any desired position, yet provide ready access to the preparatory under cutter without disturbing said guide-bar.

The standards G' , which carry the bearings for the regular upper cutter G , have pivoted to them at opposite sides of the machine, at n , the two arms n' , between which is bolted or otherwise secured to form a sort of yoke the cross-bar n^2 . (Shown on an enlarged scale in Figs. 5 to 8.) This cross-bar, preferably at its front side, is provided with a T-slot n^3 to receive the heads of a series of clamping devices or bolts n^4 , each of which is extended through a slot n^5 in an adjustable presser-block n^6 , formed with an inturned end or foot n^7 at its lower end, along the under side of which is formed a raised projection or guide-rib n^8 . (See Fig. 6.) To the lower ends of these presser-blocks n^6 and fitted to the guide-ribs n^8 are applied the presser-shoes n^9 , fitted to be moved horizontally with relation to said blocks n^6 toward and from the upper cutter G . These shoes each have a T-slot n^{10} to receive the head of an adjusting and clamping bolt n^{11} , extended upwardly and slightly diagonally through the block n^6 , to which it is attached, and is provided at its upper end with a nut, as shown.

It will be noticed that the T-slots n^{10} in the presser-shoes are inclined downwardly away from the cutter G , so that when the shoes have once been clamped in position they cannot accidentally loosen and be moved inwardly and possibly injure the rotating cutter, for if the clamping-bolts should slacken in the least any tendency of the shoes to move toward the cutter would cause the downwardly-inclined T-slots to immediately take up the looseness and hold the shoes firmly in position. The presser-shoes are thus horizontally adjustable toward and from the upper cutter G in order that they may be moved into proper positions, with relation to various kinds or shapes of cutters employed and, with their blocks n^6 , are vertically adjustable on and with relation to the hinged cross-bar n^2 to permit the shoes to be raised or lowered, as necessary, relatively to each other to rest upon and adapt themselves to various irregularities in the upper surface of the stock when the machine is being run for moldings. The presser-blocks n^6 are also swiveled or made to swing about their clamping-bolts n^4 , as represented by dotted lines, Fig. 6, to permit the presser-shoes to assume angular positions adapted to rest upon inclined or angular surfaces on the stock being run through the machine. All the presser-shoes of course move vertically with the swinging cross-bar n^2 .

Referring particularly to Figs. 2 and 5, the swinging arms n' are prolonged beyond the cross-bar n^2 and have secured to their outer ends the weight-supporting bar r , pivotally bolted at r' to one of the said arms and slot-

ted at r^2 at the end of the other arm to receive the bolt r^3 . By slackening the bolt r^3 the bar r , with its weight, may be turned about r' as a pivot into a vertical position out 5 of the way to thereby permit convenient removal of the usual shaving-hood (not shown) and ready access to the presser-shoes for adjustment. The bar r sustains the weight R , which presses the shoes n^9 down upon the 10 stock, and the said bar r is extended at its ends beyond the arms n' . When the stock is run through one side of the machine and is acted upon by the presser-shoes at one end of the cross-bar n^2 , the weight R may be run out 15 on the extended end of the bar r at that side of the machine (see Fig. 5) into a position where it will counterbalance the unsupported part of the frame and shoes and cause the shoes which are over the stock to bear evenly 20 and properly thereupon.

Referring particularly to Fig. 2, it will be seen that the side-head bearing-block e^1 is provided with the usual swinging chip-breaker e^4 , (see Fig. 11,) and it will also be seen that 25 said block is provided with a screw-shaft e^5 , provided at its front end with a handpiece e^6 , by which it may be rotated, and at its rear end is surrounded by a spiral spring e^7 , interposed between the inner face of said bearing-block and a washer and nut e^8 , threaded upon the inner end of the said screw. This screw passes through a threaded slide-block e^9 , to 30 which may be secured, as by a bolt e^{10} , (see Fig. 2,) a sliding chip-breaker or short guide 35 e^{11} , which for some classes of work is preferable to the swinging chip-breaker e^4 usually employed. Either the swinging chip-breaker or the sliding guide e^{11} may be removed at will when not desired for use. The sliding 40 guide e^{11} is adjustable—that is, made to slide toward and from the longitudinal center of the bed of the machine by rotation of the screw e^5 —and the spring e^7 permits the said shaft, with its guide, to yield against any inequalities in the stock when necessary. The 45 guide e^{11} may also be made to act against the stock with greater or less pressure to keep it against the continuous guide m by compression of the spring e^7 by rotation of the shaft e^5 . 50 We have also shown a short guide o , mounted upon a screw-shaft o' in a manner similar to the mounting of the guide e^{11} , the screw o' being provided at the front side of the machine with an operating-handle o^2 and at the 55 rear side of the machine surrounded by a spring o^3 , interposed between the frame A and the nut o^4 , threaded upon the rear end of the screw. The guide o is worked back and forth toward the longitudinal center of 60 the bed by rotation of the screw o' , and it, with its screw, is free to yield to inequalities in the stock by the spring o^3 .

Referring to Figs. 1, 2, and 12, the bearings h for the regular under cutter H at 65 the rear end of the machine are mounted in suitable guideways upon adjusting devices, preferably in the form of screws h' , by means

of which said bearings are made vertically adjustable. The bearings h are provided with depending arms h^2 h^2 , provided at their 7c outer sides with guideways for the vertically-sliding bars h^3 h^3 , provided at or near their lower ends with inwardly-projecting ears h^4 , which rest upon the shouldered heads h^5 of the screw-bolts h^6 , passed through said ears 75 and screwed into ears h^7 on the lower inner ends of the depending arms h^2 . (See Fig. 12.) The sliding bars are slotted to receive the fixed bolts h^8 , which constitute clamping devices to clamp the sliding bars in position. 80

To the lower ends of the sliding bars h^3 are pivoted or hinged at t the brackets t' on and depending at the sides from the end table t^2 , the latter being normally retained in its elevated position, Figs. 1 and 12, by means of 85 the hinged clamp-arms t^3 , hinged to its frame and provided with hand-screws t^5 , adapted to act upon the lugs t^6 on the outer sides of the table-brackets t' . By slackening the screws t^5 and throwing the clamp-arms t^3 back upon 90 their hinges the table t^2 may be turned down on its hinges into its dotted position, Fig. 1.

The cutter H is adjusted by means of the screws h' to vary the depth of cut, and the table t^2 goes with it, so that in whatever adjusted position the cutter may be the table is always in proper position with relation to it. The table may, however, be adjusted independently of and with relation to the cutter by means of the screws h^6 . 100

This invention is not limited to the particular arrangement or construction of parts herein employed for the purposes of explaining this invention, for it is evident the same may be varied without departing from the invention. 105

Should two independent guide-bars be used instead of the single continuous guide-bar herein shown, the pin or equivalent adjusting devices may still be used to advantage, 110 and said adjusting devices may be used with any other guide bar or bars without departing from the scope of this invention.

Having described our invention embodied in one of its forms and without restricting ourselves to details, what we claim, and desire to secure by Letters Patent, is—

1. In a planing-machine, the combination with the bed, an outer edge guide-bar mounted thereon and extending continuously from 115 end to end thereof, and means for identical adjustment of each end of the guide-bar independently of the other, of feed-rollers, upper and under rotary planers journaled in bearings on said bed, said planers extending 120 across the table intermediate the ends of said continuous guide-bar, means for adjusting said planers toward and from each other, and means for removing the under planer bodily, without any disturbance of said guide-bar in 125 any of its adjustments, substantially as described.

2. A planing-machine, containing the following instrumentalities, viz: a frame; a bed

thereon; a horizontal side-head support; a guide-carrier longitudinally movable thereon; adjusting devices between said carrier and its support, consisting of a series of stop-surfaces on one and a coöperating positioning device on the other, to retain said carrier in adjusted position on said support; a longitudinal guide-bar connected at one of its ends with said carrier, and at its opposite end with said bed, substantially as described.

3. A planing-machine, containing the following instrumentalities, viz: a frame; an upper cutter; feed-rollers; a cross-bar arranged close to said cutter and hinged and freely movable about a horizontal axis, and a series of presser-shoes adjustably secured to said hinged bar and movable with relation thereto both vertically and to vary their angular positions to accommodate the varying upper surface of the stock, substantially as described.

4. In a planing-machine the combination of the following instrumentalities, viz: a frame; feed-rollers, and upper and under cutters; a vertically-movable hinged cross-bar arranged in front of said upper cutter, and provided with a longitudinal slot, and a series of presser-blocks, clamping-bolts therefor passing through said slot, presser-shoes mounted to slide longitudinally of the bed on said presser-blocks, and clamping-bolts therefor passing vertically through said blocks, substantially as described.

5. In a planing-machine, the combination with a cutter, a vertically-movable cross-bar arranged in front of said cutter, of a series of presser-blocks secured to and adjustable vertically with relation to said cross-bar; and presser-shoes provided with clamping-surfaces inclined downwardly from said cutter and clamping-bolts coöperating therewith by engagement with said inclined surfaces, whereby accidental movement of said presser-shoes toward said cutter is prevented, substantially as described.

6. In a planing-machine, the combination with a frame, a bed, and a laterally-adjustable guide-bar, of a rotatable screw-shaft threaded to and to move said guide-bar, and a spring to permit endwise yielding movement of said screw together with the guide-bar, substantially as described.

7. In a planing-machine, the combination with a guide-bar, and a positioning device carried thereby, of a series of separated stop-surfaces coöperating with said positioning devices, and adjusting devices to vary the position of said series of stop-surfaces, substantially as and for the purpose specified.

8. A planing-machine, containing the following instrumentalities, viz: a frame; a bed; feed-rollers; an upper cutter; a cross-bar ad-

jacent thereto and pivoted to swing about a horizontal axis extending crosswise said bed; one or more presser-shoes attached to said cross-bar; a weight-supporting bar pivoted to said cross-bar and adapted to swing about an axis extending longitudinally said bed into an upright position to permit access to the parts beneath, substantially as described.

9. In a planing-machine, the combination with the bed, of a rotary under cutter, bearings for said cutter, the bed being recessed to hold said cutter and bearings within it, a guide-bar extending longitudinally of the bed across said under cutter and adjustably secured at its ends on opposite sides of said under cutter, under-cutter bars overhanging said under cutter when the latter is in operative position in the bed, and transverse horizontal ways for the endwise bodily removal of the under cutter transversely through the bed, substantially as described.

10. In a planing-machine, a bed transversely recessed on its upper side to receive a rotary under cutter, horizontal ways extending transversely of said bed, end bearings mounted to slide in said ways, and a rotary under cutter mounted in said bearings and removable bodily endwise therewith from the bed of the machine, substantially as described.

11. In a planing-machine, a bed, having a recess in its upper side extending transversely of the machine, a housing, provided at its ends with necks coöperating with seats formed in the frame of the machine, means for vertically adjusting said housing, longitudinal ways in the sides of said housing, end bearings mounted to slide in said ways, and a rotary under cutter journaled in said bearings, substantially as described.

12. In a planing-machine, a bed transversely recessed on its upper side to receive a rotary under cutter, horizontal ways extending transversely of said bed, end bearings mounted to slide in said ways, and a rotary under cutter mounted in said bearings and removable bodily endwise therewith from the bed of the machine, opposite vertical sockets adjacent said ways, cutter-bars or chip-breakers mounted in said sockets to overhang said under cutter, and means for vertically adjusting said cutter-bars with relation to the cutter, substantially as described.

In testimony whereof we have signed our names to this specification in the presence of two subscribing witnesses.
